EXPLOSIVE

John A. Ruth, Clinton, Ind., assignor to Olin Mathieson Chemical Corporation, a corporation of Virginia

Application January 10, 1952, Serial No. 265,830

2 Claims. (Cl. 102—20)

This invention relates generally to explosives and more particularly to novel explosive shaped charges having improved properties.

It has been known in the blasting art that the energy developed by an explosive charge can be concentrated and a greater depth of penetration achieved by modifying the shape of the surface of the charge which faces the media to be blasted. For instance, the surface is provided with a cavity therein which may be conical, pyramidal, parabolic or the like; charges having such cavities being referred to hereinafter as shaped charges. This phenomenon is advantageous in numerous blasting operations such as, for example, in perforating the casing and media surrounding oil well bore holes, in some mining operations, tapping metallurgical furnaces and in armor piercing projectiles. In some of these operations the media must be penetrated to a relatively great depth without destruction of a large area of the surface thereof and, in most instances, the blasting must be accomplished with a relatively small explosive charge. It has also been known that even greater penetration is attained with shaped explosive charges provided with a non-explosive covering or liner conforming to the shaped surface thereof. This improvement has been attributed to the projection of particles of the liner at a high velocity when the explosive is fired. The shaped charges utilized in blasting operations of this type have been formed heretofore from secondary explosive compositions having a relatively high degree of brisance such as trinitrotoluene, pentaerythritol tetranitrate, cyclotrimethylenetrinitramine or mixtures thereof. While the foregoing explosives have been used extensively because of their relatively high brisance, it has long been recognized that greater penetration than is obtainable with shaped charges of these explosives would be advantageous in any of the foregoing types of blasting operations and particularly so in the perforation of oil well bore holes and in armor piercing projectiles where maximum depth of penetration per unit amount of explosive charge is important.

It is an object of this invention therefore to provide an improved explosive charge having improved penetrating properties. Still another object of this invention is to provide an improved method for perforating the walls of oil well bore holes. A further object of this invention is to provide novel explosive shaped charges. It is a still further object of this invention to provide explosive charges of high brisance and a method for using them.

In accordance with this invention, the foregoing objects as well as others which will become apparent from the following description are accomplished by providing methylenedinitramine as an explosive. Methylenedinitramine in granular or crystalline form can be formed readily into shaped charges by the methods used heretofore with granular trinitrotoluene and the like and the resulting charge has great penetrating power and other advantages, which will become apparent from the detail description hereinafter. This invention further contemplates an improved process for perforating various media such as, for

instance, the wall of oil well bore holes, armor and similar materials with shaped charges of methylenedinitramine.

Methylenedinitramine can be prepared by a series of reactions in which methylenebis-N-acetamide, methylenebis-N-acetamide mononitrate, methylenebis-N-(N-nitro)-acetamide, the barium salt of methylenedinitramine and finally methylenedinitramine are formed in that order, in accordance with the process described by Brain and Lamberton published in the Journal of the Chemical Society, June 1949, pp. 1633-5.

The surface of the methylene dinitramine charge facing the medium to be perforated is modified to concentrate the energy developed by the explosion thereof in the known manner, the particular configuration most advantageous varying with the type of operation in which the charge will be utilized. An explosive charge having a cavity in the shape of an inverted cone in a surface thereof is particularly advantageous in tapping metallurgical furnaces. Armour piercing projectiles containing shaped charges of methylenedinitramine in which the cavity is parabolic are particularly effective. In each instance it is preferred that the cavity in the charge be provided with a non-explosive covering or liner. The liner may be made from metal, ceramic, plastic or similar non-explosive material and should conform substantially to the shaped surface of the explosive charge.

In order to more fully describe and to clarify this invention, the following is a description of one embodiment thereof:

Referring to the accompanying drawing, a longitudinal sectional view of an oil well casing 16 is shown with a perforating device 13 positioned therein and substantially adjacent to the wall 12 of the casing 16. The perforating device 13 is composed of two external glass parts 1 and 3. The base portion 1 contains a relatively small pressed explosive charge 5 of methylenedinitramine crystals separated from the larger pressed charge 10 of wax coated methylenedinitramine crystals by means of a paper disk 6. The coating of wax is applied to the methylenedinitramine crystals to be used for charge 10 by a process which comprises mixing a solution containing about two parts of a microcrystalline petroleum wax known to the trade as "Superla No. 3 Special" and which has a melting point of about 76° C. dissolved in about 80 parts by weight carbon tetrachloride with about 50 parts methylenedinitramine and evaporating the carbon tetrachloride therefrom by means of an air steam. A conical shaped cavity is formed in the surface of charge 10 and covered with a brass liner 7. The flange 4 of the open end of the base portion 1 of the device 13 is coated with a layer of pitch 17 and inserted into the flange 18 of nose portion 3 forming a friction fit and water-proof juncture therewith. The ogive 19 of nose portion 3 of the perforating device 13 extends through an opening in aluminum foil 8 and is supported thereby. A primacord 9 extends through opening 11 in aluminum foil 8 and around the base portion 3 between protuberances 2 and 15 and is drawn tightly through opening 14 in aluminum foil 8, thus supporting and exerting pressure against the base portion 1 of the device 13 and wedging the entire assembly in position with respect to the aluminum foil 8. When it is desired to fire the methylenedinitramine charges 5 and 10 the primacord 9 is initiated by means of a conventional electric detonator or any other suitable means which initiates untreated charge 5 of methylenedinitramine which fires the main charge 10. A jet of metal from liner 7 as well as the energy developed by the explosive charges 5 and 10 are projected against the wall 12 of casing 16 perforating it and penetrating into the media thereabout.

It has been found that methylenedinitramine shaped

charges have greater penetrating properties than any of the explosives disclosed for this purpose. Methylene-dinitramine has been found to have a strength of about 1.5 as compared to 1.0 for trinitrotoluene as determined in the Ballistic Mortar Test and a brisance of about two times that of trinitrotoluene in the Lead Block or Trauzl Block Test. The packing density of methylenedinitramine is about 1.7 and is greater than that of cyclotrimethylenetrinitramine which is an important property as the brisance of an explosive charge increases with increase in packing density thereof. The velocity of detonation of methylenedinitramine at a density of about 1.0 is about 5600 meters per second as compared with 4870 meters per second for TNT which is another important property thereof as a high detonation rate is advantageous in blasting operations utilizing shaped charges.

As indicated hereinbefore, shaped charges of methylenedinitramine are superior to the explosives heretofore proposed for tapping metallurgical furnaces. In tapping furnaces with explosive shaped charges, a hole is usually drilled entirely through the fire clay plug in the tap hole. This leaves only a relatively thin barrier of solid metal adjacent the inner end of the plug to prevent flow of the molten metal from the furnace. The shaped charge is rammed into the hole thus formed in the plug and initiated to perforate the solid metal incrustation. The explosive charge is usually insulated by covering it with insulating material or by ramming insulating material into the hole prior to insertion of the explosive. When methylenedinitramine shaped charges are utilized it is not necessary to drill entirely through the fire clay as these charges will penetrate an appreciable thickness of the clay as well as the solid metal. Usually, depending upon the size of charge used, the hole need extend through only about two-thirds of the thickness of the plug thus leaving an added barrier against flow of the molten metal and reducing the hazard involved in these processes. The methylenedinitramine can be initiated by the heat from the furnace or a detonator can be embedded in the charge and ignited electrically to initiate the explosion thereof, if desired. The methylenedinitramine shaped charge can be formed by pressing into a suitable container provided with a concave surface and insulated in accordance with conventional methods.

Methylenedinitramine because of its increased penetrating properties can also be used advantageously in armor piercing projectiles provided with a concave surface at the striking end thereof and also for forming "drill holes" or channels in mine walls for blasting cartridges.

Numerous variations from the details of the foregoing embodiments such as, for example, forming the perforating device from plastic or metal, or substituting other types of containers for the perforating device can be made without departing from the spirit of this invention.

In the embodiment for perforating the media surrounding oil well bore holes, other means for supporting the perforating device can be provided, the one described being only a preferred and convenient method. In this particular method, however, the primacord serves a two-fold purpose of supporting the device 13 as well as serving to initiate the methylenedinitramine charges. Likewise, initiating charges other than methylenedinitramine

such as lead azide might be utilized for the igniter explosive charge 5. Waxed methylenedinitramine is preferably utilized as the shaped charge 10 because it has a lower impact sensitivity than uncoated methylenedinitramine and can be handled and shipped with less danger of inadvertent explosion. Uncoated methylenedinitramine can be utilized satisfactorily provided caution is observed in handling.

While in the foregoing embodiment a microcrystalline petroleum wax was utilized, other waxes such as ceresin, and paraffin waxes having a suitable melting point of about 70° C. or higher can be substituted therefor. Waxed methylenedinitramine can be utilized entirely and the more impact sensitive charge replaced thereby if sufficient means are provided for initiating the desensitized explosive. Shaped charges of methylenedinitramine are effective whether or not minor amounts of other explosives such as cyclotrimethylenetrinitramine or pentaerythritol tetranitrate are included.

It should be apparent from the foregoing description that this invention accomplishes its objects and provides an improved explosive charge and an improved process wherein greater depth of penetration without destruction of large surface area of the medium to be perforated or for penetration of heavy armor is attained.

Having thus described the invention what is claimed and desired to secure by Letters Patent is:

1. A shaped charge of methylenedinitramine having a wax coating and compressed to a packing density of at least 1.7, and combined therewith a second charge of uncoated methylenedinitramine, said shaped charge having a strength of at least 1.5 times as great as that of trinitrotoluene and a detonation rate greater than that of trinitrotoluene.
2. A well bore hole perforating device comprising a container having a base portion and a nose portion frictionally fit together, an impact sensitive explosive charge and a charge of wax coated methylenedinitramine compressed to a density of at least 1.7 in said container, the surface of the methylenedinitramine charge facing the nose portion having a cavity therein and a non-explosive liner covering and in engagement with the surface of said cavity.
